UNITED STATES PATENT OFFICE.

CHRISTOPHER J. LAKE, OF BRIDGEPORT, CONNECTICUT.

MOTOR.

1,279,367.

Specification of Letters Patent: Patented Sept. 17, 1918.

Application filed January 28, 1918. Serial No. 214,172.

To all whom it may concern:

Be it known that I, CHRISTOPHER J. LAKE, citizen of the United States, and resident of Bridgeport, in the county of Fairfield and 5 State of Connecticut, have invented certain new and useful Improvements in Motors, of which the following is a specification.

This invention relates to internal combustion motors, and it is directed particularly to improvements applicable with means such as are disclosed in my earlier Patent No. 971,760, in which moistened air, heated in the cylinder jacket, is caused to contribute propulsive energy to the piston, 10 besides functioning as a cylinder cooling medium.

Briefly stated, my said improvements consist of means, operable by the motor, whereby (1) the velocity of air flow to the cylinder casing or jacket may be varied, and thus its volume and pressure increased or decreased both for satisfying cooling requirements and for subsequent introduction to the working cylinder, and (2) where- 20 by variable pressures of air are created and caused to concomitantly regulate the proportion of liquid fuel introduced into the cylinder, and the proportion of water injected into the cylinder jacket.

Especially in the case of aeronautical motors, which are required to function under varying conditions of the atmosphere, ranging from normal pressures near the earth, to more tenuous stages at higher altitudes, difficulty has been experienced in attempting 35 to adapt the present day motors for efficient operation under all conditions of atmospheric density. In fact, with respect to the very thin air of high altitudes, it is doubtful whether others have yet devised means for 40 amply charging the cylinders with air.

An air compressor is run by the motor, but means are provided by me, under the control of the operator, whereby the speed of the 45 compressor can be varied, relatively to the motor speed, so that when operating for example in the presence of lighter air, the greater activity of the compressor will enable it to supply the requisite volumetric 50 charges for efficient power impulses, as well as for the other purposes set up in my said former patent.

Other features and advantages of my said invention will hereinafter appear.

In the drawing:

Figure 1 is a side vertical section of a motor having my improvements.

Fig. 2 is a rear elevation thereof, and Fig. 3 is a detail plan view, in section, of the compressor.

In the present example of my improved motor, I have shown a cylinder 1, having a cooling jacket 2. The piston, 3, is linked with a cross-head 4 by a connecting rod 5, said cross-head traveling upon guides 6, and, 55 by means of pitman 7, operating a crank-shaft 8, which latter may carry or operate a propeller 9, or otherwise deliver its power.

The cylinder in this instance is intended to be double acting, *i. e.*, provided with 70 upper and lower intake valves, respectively indicated at 10 and 11, in order that the piston may receive a power impulse for each stroke, and also said cylinder is provided with two exhaust ports, 12 and 13, respectively, to carry off the expended power media. The particular characteristics and arrangements of these valves and exhaust ports will be referred to hereinafter.

Mounted upon the crank-case 14 is a compressor 15, which is driven by change speed mechanism from the crank-shaft 8; a shift lever 17, to be handled by the operator, serving to control the speed of the compressor to any desired set variations relatively to the 85 speed of the crank-shaft, or to enable said compressor to run at the same speed as the crank-shaft. The compressor is shown as a rotary pump, having vanes 15^a, and shaft 15^b, the latter carrying a friction wheel 15^c, to be operated by a disk 16; said wheel and disk representing the change speed mechanism. Air is supplied to the jacket 2, as through a tube 18, valve casing 19 and valve 20, said valve having a hollow stem 21, 90 which extends outside the valve casing, and communicates, as by a flexible tube 22, with a water tank 23. Radial orifices 24 in the valve 20 communicate with the interior of the hollow stem, said orifices normally closing against the valve seat 25 when the valve is closed, and permitting the passage of water to the jacket, concurrently with the inflow of air, when the valve is opened. A needle valve 26 is provided for the hollow 95 valve stem 21, whose adjustment regulates the proportion of water, under any given pressure, that is to be injected into the

jacket in the period during which the valve 20 is open. The valve 20 may be actuated as by a bell-crank 27, which is operated by a cam rod 28.

5 A pipe 29 communicates from tube 18 to a liquid fuel tank 30 and water tank 23. Thus equal pressure from the compressor is applied both to the water and fuel supplies.

Fuel from tank 30 passes through tube 31 10 to a hollow stem 32 carrying valve 10, said valve having radially opening orifices 33, which, when the valve is open, conduct fuel to the cylinder, and which, when the valve is seated, are closed against the valve-seat.

15 A needle valve 34, in the valve-stem 32, provides adjusting means for regulating the flow of liquid fuel through said hollow stem. The valve 10 may be controlled as by a rocker arm 35, operated as by a cam-

20 rod 36.

Heated air, or admixture of air and steam, is admitted to the cylinder through valve 10 concurrently with the fuel, to constitute an explosive charge, whose propulsive ef-

25 effect is enhanced through the pressure created in the jacket by the transference of heat thereto from the cylinder, which also reacts with the exercise of a consequent cooling influence upon the cylinder. In

30 this power stroke the piston moves to the opposite end of the cylinder. For the return stroke of the piston the valve 11 opens and admits the expanding pressure of the heated air and steam from jacket 2 to the

35 other side of the piston, and thus this return stroke becomes also a power stroke, though in lesser degree.

The piston 3 is shown in full lines in Fig. 1, as moving upwardly from its lower,

40 dotted position, under the influence of the pressure medium received from jacket 2 through valve 11, which has been opened as by rocker arm 37, actuated by cam-rod 38; the piston thence continuing its move-

45 ment to the end of the stroke, indicated by the upper representation in dotted lines. During this stroke of the piston, the ex-

haust port 13 has remained closed, while the exhaust port 12 has been held open for the 50 escape of burnt gases from the upper end of the cylinder,—the residue of an exploded charge under the influence of which the piston had made its preceding power stroke in the other direction.

55 While the piston is passing the port 12 the valve 10 is opened, whereby liquid fuel is admitted to the combustion chamber, under pressure, through hollow stem 32 and orifices 33, and, at the same time, air, or

60 mingled air and steam, are enabled to enter said combustion chamber, also under pressure from jacket 2, as through a communicating opening 39, carburetion occurring as the combustion supporting medium is forced

65 into the chamber, and is, co-incidently

with its entry, impregnated with tiny jets of diffusing fuel from the radial orifices 33.

The period during which valve 10 remains open is limited to the time occupied by the piston in moving to about a point 70 near the upper edge of the port 12, said port becoming closed at about the time when valve 10 opens. The combustible charge which has been admitted to the upper portion or combustion chamber of the cylinder, 75 is then, in the remainder of the piston stroke, further compressed, prior to ignition as by spark plug 40, to provide the impulse for the return power stroke.

The exhaust ports 12 and 13 are respectively controlled by valves, here indicated as slide-valves 41 and 42. I have shown the valves 41, 42 as connected together by a link 43, and actuated by a single cam-rod 44.

The arrangement of said valves is such that they serve to open one of the exhaust ports while closing the other one. Thus, when the port 12 is closed, as described, in the course of the upward stroke of the piston, the port 13 has, in the same action, been opened, and thereby the expanded fluid medium, whose energy had carried the piston through its upstroke, is allowed to escape during the final portion of said upstroke, and also during the first portion of the 95 downwardly returning power stroke.

The exhaust ports may connect with a manifold 45, as a common discharge channel for the expanded products of both power media, and into this channel I may introduce 100 the nozzle 46 of a relief pipe 47 that communicates with the source of compressed air supply. Said relief pipe is provided

with a safety valve 48, adjustable to open when the pressure exceeds cylinder requirements, and then the overplus pressure is relieved through pipe 47, whose nozzle is inclined in the direction of flow taken by the exhaust products, to, by entraining action, assist in scavenging the working chambers 110 of the cylinder, and also to exercise a cooling influence upon the exhaust gases.

As will be apparent from the foregoing description, air under equal pressure is delivered by the compressor to the jacket 2, the fuel tank 30 and the water tank 23, the degree of pressure varying according to the speed at which the compressor is driven.

Obviously, by means of the change speed mechanism employed (which may be of any known type), the compressor speed may be increased or diminished to suit the motor requirements, according to the density or

tenuity of the atmosphere in which it is operating, and thus, for example, a motor at an elevation of 20,000 feet, may be caused to operate its compressor at a sufficiently increased rate of speed above that of the crank shaft, to insure the delivery of full cylinder pressure charges.

Variations may be resorted to within the spirit and scope of my said invention and parts thereof used without others.

I claim:—

5 1. The combination, with a motor, of a compressor driven thereby to deliver an elastic power medium to said motor, and manually controlled means for varying the speed of said compressor relatively to said 10 motor.

15 2. The combination, with a motor, having a cooling jacket, of a compressor driven by said motor to deliver air to said jacket, to be heated therein, and to be delivered therefrom to said motor, and manually controlled means for varying the speed of said compressor relatively to said motor.

20 3. The combination, with a motor, having a cooling jacket, a liquid fuel supply to said motor, and a water supply to said jacket, of a compressor driven by said motor to deliver air to said jacket and apply pressure upon said fuel and water supplies, means for communicating mingled air and water to 25 said motor from said jacket, as heated in the latter, and manually controlled means for varying the speed of said compressor relatively to said motor.

25 4. The combination, with a motor, having a cooling jacket, a liquid fuel supply to said 30 motor, and a water supply to said jacket,

of a compressor driven by said motor to deliver air to said jacket and apply pressure upon said fuel and water supplies, a double acting piston in said motor, separate 35 means for communicating mingled air and water from said jacket, as heated in the latter, alternately to opposite sides of the piston, and manually controlled means for varying the speed of said compressor relatively to said motor.

40 5. The combination, with a motor, having a cooling jacket, a liquid fuel supply to said motor, and a water supply to said jacket, of a compressor driven by said motor to deliver air to said jacket and apply pressure upon said fuel and water supplies, a double 45 acting piston in said motor, separate means for communicating mingled air and water from said jacket, as heated in the latter, 50 alternately to opposite sides of the piston, separate exhaust means for the power media, and manually controlled means for varying the speed of said compressor relatively to said motor.

55 Signed at borough of Manhattan, in the city, county and State of New York, this 26th day of January, A. D. 1918.
